HIS ATTORNEY.

Therefore it is an object of the invention to provide a device for removing moisture from compressed air which is particularly effective in removing moisture from air which has been cooled to a temperature below that of the available cooling water.

UNITED STATES PATENT OFFICE

2,577,176

AIR DRIER

James H. Anderson, Easton, Pa., assignor to Ingersoll-Rand Company, New York, N. Y., a corporation of New Jersey

Application December 16, 1947, Serial No. 792,065

2 Claims. (Cl. 62—137)

1

This invention relates to a dryer device, and more particularly to a compressed air dryer.

Driers of this type are used to remove moisture from compressed air before its use in air tools and air operated gauges to avoid the undesirable effects of condensation in such instruments. Also, moisture is removed from compressed air to prevent the formation of condensate in any cooled portion of the air supply line leading to the instruments which would require that the line be drained periodically.

Existing air driers are normally comprised of a water cooled heat exchanger and a separator in series and although generally satisfactory they have certain inherent limitations, particularly in that the air cannot be cooled below the temperature of the available cooling water. This being true, if at any time the compressed air, after leaving the dryer, is subjected to a temperature lower than that of the cooling water, further condensation will occur.

It is, accordingly, one object of my invention to dry the air sufficiently to avoid the formation of any condensate in the air after it has left the dryer.

Another object is to regain a part of the pressure loss normally incurred by the pressure fluid in the drying process.

A further object is to restore a part of the temperature loss normally incurred by the pressure fluid during the drying process.

Other objects will be in part obvious and in part pointed out hereinafter.

In the drawings accompanying this specification and in which similar reference numerals refer to similar parts,

Figure 1 is an outside view, in elevation, of the air dryer constructed in accordance with the practice of the invention and adapted to a fluid brake,

Figure 2 is a side elevation, partly in section, of Figure 1,

Figure 3 is a transverse view taken through Figure 2 on the line 3—3,

Figure 4 is a transverse view taken through Figure 3 on the line 4—4, and

Figure 5 is an elevation, partly in section, of the dryer adapted to a centrifugal blower.

Referring to the drawings and more particularly to Figure 1 and its associated views, 19 designates, in general, a compressed air dryer comprising a regenerative heat exchanger 11 mounted on an expansion engine, in this instance a turbine 12, which is supported by a fluid brake housing 13.

2

In the present form of the invention, the heat exchanger 11 is shown encased by insulating material 14 and has a supply conduit 15 for conveying pressure fluid to a nozzle 16 of the expansion turbine 12. The nozzle 16 is mounted in the customary manner with respect to a horizontally positioned wheel 17 in the turbine housing 13 so that pressure fluid expanding through the nozzle will be directed against turbine blades 19 to rotate the wheel 17. In this manner, that portion of the pressure energy of the fluid that is converted to kinetic energy is dissipated by doing mechanical work, thereby preventing the reheating of the fluid by such kinetic energy if it were dissipated by friction.

Within the brake housing 13 is a fan 20 which is secured to a vertical turbine shaft 21 mounted on bearings 22. The fan 20 is partially immersed in oil or a similar fluid which is supplied thereto through a hole 23 in the housing 13 and serves to retard the rotary motion of the fan 20 thereby affording resistance to rotation of the turbine wheel 17. In order to further retard the rotary motion of the fan 20, the base 24 for the housing 13, has a horizontal annular recess or groove 25 therein having plates 26 that extend radially inward from the outer edge of the groove thereby forming a stationary fan similar in design to the fan 20 and positioned in an opposed relation thereto. The lower edge of the fan 20 and the upper edges of the plates 26 are positioned in close proximity so that a viscous drag exists in the oil therebetween, and also so that the oil is agitated in the groove 25. The oil thus agitated forms a mist or vapor which rises or is forced upwardly by the rotation of the fan and serves to lubricate the bearings 22. A seal 27 encircling the upper end of the shaft 21 prevents leakage of oil into the turbine 12 and a removable plug 28 in the hole 23 prevents leakage of the oil from the lower portion of the housing.

In the present instance, the turbine and fluid brake are designed so that the turbine blade velocity is approximately one half the velocity of the pressure fluid as it leaves the nozzle 16. This means, of course, that the pressure fluid will leave the blades 19 with a tangential component of velocity sufficient to allow the pressure fluid to move clear of the blades 19. At this velocity the condensate formed in the pressure fluid, due to the expansion cooling, will be separated therefrom.

Disposed on the side of the wheel opposite the nozzle 16 is one end of a discharge conduit 29

and the other end portion thereof loosely encircles the supply conduit 15 to define a flow path therebetween. This regenerative arrangement permits expanded fluid issuing from the turbine blades to be conveyed to the exterior of the supply conduit 15 thereby bringing such fluid into a heat exchanging relationship therewith for initially cooling pressure fluid flowing to the nozzle. In the lower or turbine end portion of the discharge conduit 29 means are provided for the removal of condensate from the compressed air flowing through the conduit 29. For the sake of simplicity of illustration this means is shown as being a sharp turn or U 30 in the discharge conduit whereby the condensate is ejected from the pressure fluid flowing theretoward. A hole 31 in the lower portion of the conduit serves to drain condensate therefrom.

In the modified form of the invention which is shown in Figure 4, the air dryer is identical in construction to the aforescribed dryer except that the turbine drives a pump or centrifugal blower 32. In this form of the invention, a conduit 33 serves as a means to convey warmed pressure fluid from the exterior of the supply conduit to the blower 32 wherein a portion of the expansion energy of the pressure fluid transmitted to the turbine is regained. Also the blower, like the fluid brake, serves as a means driven by the expansion engine 12 to dissipate the output or energy thereof.

It is now obvious to those skilled in the art that this regenerative arrangement for the heat exchanger 11, interconnected with the turbine 12, presents a great advantage in that the stable or operating temperature of the cooling medium, before contact with the supply conduit 15, is dependent on the construction of the dryer. That is, a temperature differential exists between the compressed air in the supply and discharge conduits 15 and 29 due to the temperature decrease incurred by the air expanding through the nozzle 16. Thus, because of the regenerative effect, the temperature of the cooling medium will continue to decrease until the quantity of heat absorbed by the exchanger 11 from the atmosphere is equal to that given up by the compressed air in expanding through the nozzle 16 and doing mechanical work. The value of the operating temperature of the cooling medium for any one dryer is, of course, dependent on various particulars in design for that dryer, such as the construction of the turbine, and the amount of heat transfer surface in the heat exchanger.

There is also an added advantage in the use of the regenerative heat exchanger in that a portion of the temperature loss incurred by the com-

pressed air during the drying process is restored in the heat exchanger. The degree of rise in temperature of the compressed air cooling medium in the exchanger is, of course, dependent on the design of the heat exchanger, which in this instance, for the purpose of illustration, was shown in a simple form.

While I have shown and described one form of my invention, it is to be understood that various changes and modifications may be made therein without departing from the spirit of the invention as set forth in the appended claims.

I claim:

1. In a pressure fluid dryer, an expansion turbine, a supply conduit for conveying pressure fluid to the turbine, a discharge conduit for the turbine to convey all fluid expanded therein to the exterior of the supply conduit, means in the discharge conduit for ejecting condensate from pressure fluid flowing therethrough, means for draining condensate from the discharge conduit, a centrifugal blower actuated by the turbine, and means for conveying all pressure fluid from the exterior of the supply conduit to the blower.

2. In a pressure fluid dryer a rotary compressor, a turbine mounted on said compressor for driving the compressor, a conduit for supplying pressure fluid to drive the turbine, a heat exchanger mounted on the turbine and encircling said conduit, a discharge conduit for conveying all the fluid discharge from the turbine to said heat exchanger, said discharge conduit having a sharp turn therein for separating moisture from fluid flowing theretoward, and a drain located at said turn for draining liquid from said discharge conduit, and means for conducting fluid from the heat exchanger to said compressor.
